GEORGE E. MAYHEW, OF CHICAGO, ILLINOIS, ASSIGNOR TO SWIFT AND COMPANY,
OF CHICAGO, ILLINOIS, A CORPORATION OF ILLINOIS

COVER LIFTER

Application filed December 22, 1930. Serial No. 503,847.

My invention relates to a novel device for removing covers from receptacles especially receptacles having self-locking lids such as are sometimes used for the storage and shipping of frozen eggs.

One of the objects of my invention is to provide a means for quickly and easily removing such covers without damage to the cover or the receptacle.

10 Frozen eggs are commonly packed in cans of thirty (30) pound capacity. One type of frozen egg can is cylindrical and provided with a self-locking lid, the lid or cover being in the form of a cap having 15 downwardly extending sides flaring outwardly and turned to provide a bead adapted to being gripped or knocked which is integral with the lid or cover to permit removal thereof. It must be borne in mind 20 that eggs after packing in cans of this type are often subjected to lower temperatures which results in the eggs expanding and bulging the sides of the can. This, of course, often results in binding the lid and 25 rendering removal difficult.

My device which is novel in construction may be better understood by reference to the drawings in which Figure 1 is a plan view, Figure 2 is a side view, Figure 3 is 30 an end view and Figure 4 is a view showing the manner of using the device. The device consists of shank 1, provided with handle 2, strap 3 and hook 4.

It is to be noted that strap or cross bar 3 is arched for greater strength, being flat at the ends 5 and 6, at which points contact is made with the cover on the can at opposite sides thereof adjacent the skirt of the cover. It is to be noted that hook 4 is bent 40 back toward the handle in order to clear the bead 7 which is integral with the skirt 8 of the cover of the can 9.

In using the device, the operator grips it by the handle 2, places the ends 5 and 6 45 of strap 3 in contact with the top of the can and inserts the hook 4 under the bead 7. An upward pull on the handle 2 removes the cover in accordance with ordinary principles of physics.

50 It will be noted by reference to Figure 4

that the distance between the hook 4 and the strap 3 is less than half the diameter of the cover. I found in practice that if this distance be increased more than half the diameter of the cover, the cover is likely to 55 become damaged and bent in removal. The peculiar construction of the hook, namely, being so attached to the shank 1 as to form an acute angle on the handle side, practically eliminates slipping which it is found occurs where the hook is not so constructed, due partly to the fact that the shank of the hook in ordinary usage contacts with the cover 8 at 10 and partly to the fact that the upward force at the hook 4 is in the direction of the shank of the hook, the components of this force being upward and inward. The flat fulcrum portions of the arched cross bar or strap 3 by bearing against the 60 top of the cover at opposite sides thereof 70 adjacent the skirt of the cover are fulcrumed on the strongest portion of the cover and consequently, the liability of injuring the cover is reduced to a minimum.

It is to be understood that changes may be made in the details of my invention without departing from the spirit thereof as defined in the claim which follows.

I claim:

A device of the class described, comprising a shank provided with a handle at one end, a relatively long arcuate strap or cross bar secured to the opposite end of the shank and extending at a right angle to the shank on opposite sides of the latter and having its ends provided with flat fulcrum portions arranged to bear upon the upper face of the cover of a can at opposite sides thereof adjacent the skirt of the cover, and a lifting hook rigidly connected to the shank 80 and extending at an acute angle to the handle of the shank.

Signed at Chicago, Illinois, this 20 day of December, A. D. 1930.

GEORGE E. MAYHEW.
